UNITED STATES PATENT OFFICE.

JAMES S. MOE, OF MASSAWINI, BARAMA, BRITISH GUIANA.

NOZZLE FOR PAINTING APPARATUS.

1,186,117.

Specification of Letters Patent.

Patented June 6, 1916.

Application filed February 26, 1915. Serial No. 14,682.

Full where it appears.

Be it known that J. James S. Moe, subject of the King of Great Britain, residing at Massawini, Barama, British Guiana, have invented certain new and useful Improvements in Nozzles for Painting Apparatus, of which the following is a specification:

My invention relates to new and useful improvements in paint distributing nozzles of the character employed in painting machines in which the paint is supplied to a nozzle or brush by a tube either from an elevated tank or from the contents of a tank under pressure.

The object of my invention is to provide a nozzle of the above described character which will absolutely prevent the accumulation of paint in the nozzle during its application, thereby securing a smooth even covering of paint.

A further object of my invention is to provide a paint distributing nozzle which may be made in various sizes and in different shapes to adapt it for use upon various kinds of wood and which will be simple in construction and durable.

With these and other objects in view, my invention will be more fully described, illustrated in the accompanying drawing, and then specifically pointed out in the claim which is attached to and forms a part of this application.

In the drawing: Fig. 1 is a perspective view of my improved paint distributing nozzle; Fig. 2 is a central vertical section of the same, more clearly bringing out the formation and arrangement of the discharge slot through which the paint passes to the article being painted; Fig. 3 is a perspective view, showing a slightly different shaped nozzle adapted for use in painting a uniformly rounded surface; Fig. 4 is a similar view, showing a nozzle adapted for use upon fluted work or moldings; Fig. 5 is a perspective view, showing a modified form of construction, the nozzle shown in Fig. 3 being adapted for the same kind of work as that shown in Fig. 1.

Corresponding and like parts are referred to in the following description and indicated in all the views of the drawing by the same reference characters.

The preferred embodiment of my invention consists of a substantially wedge-shaped, hollow body member 10 having an inlet pipe 11 leading to the central portion

of the head 12 of the body member. The body member is preferably formed of relatively heavy metal, including the head 12, spaced triangular side members 13 and 14 and bottom and top members 15 and 16. The converging edge portions of the side members are preferably provided with pairs of oppositely disposed, integrally formed, tongues 17 which are seated in recesses 18 in the side edge portions of the top and bottom members to assist in securing the parts of the body member together. All adjacent edges of the members making up the body of the nozzle are soldered or brazed together to form liquid proof joints and so prevent oil leakage of paint from the nozzle. The inlet pipe 11 is preferably threaded to receive a threaded pipe 19 having a cutoff valve 20 and in use a flexible hose leading from the paint supply tank is connected to the free end of the pipe 19 which is rigid and forms the handle of the nozzle or brush.

The wedge edge of the bottom member 15 of the body is cut-away or beveled at its outer face, as shown at 21 to such an extent as to provide a paint discharge slot 22 between it and the adjacent edge of the top member 16. This, as best shown in Fig. 2 of the drawings, also necessitates a slight beveling of the inner face of the top member 16. This bevel is preferably formed at such an angle that the slot 22 extends longitudinally and centrally of the beveled face 21 and said slot must not exceed in area the cross sectional area of the paint inlet pipe 11.

In operation, the pipe 19 is attached to the hose leading from the supply tank, not shown, the valve 20 is opened to permit the flow of paint under pressure into the body 10 of the nozzle and the nozzle is held against the surface to be painted in such a manner that the beveled face 21 bears evenly against its surface. The nozzle is then drawn along this surface to be painted, the paint being forced through the slot 22 in the form of an extremely thin ribbon and therefore evenly and smoothly distributed upon the surface. By forming the slot 22 of less cross sectional area than the inlet pipe 11, all formation of air bubbles about the discharge slot, resulting in an uneven application of the paint, is avoided as no air will at any time during the operation enter the body member of the nozzle, the supply of paint being such as to keep the nozzle completely filled at all times.

As will be apparent from the drawing, the nozzle shown in Fig. 1 can be employed only upon plane surfaced work and it will therefore be realized that I do not wish in any way to limit myself to the specific formation of the slotted edge of said nozzle as said edge may be formed in any desired manner to adapt it for use upon surfaces of different contours. For instance, in Fig. 3 I have illustrated the nozzle with an arcuate wedge edge for applying paint to curved surfaces, this type of edge of course being obtained by bending the lower portions of the top and bottom members of the body. In Fig. 4 I have shown a still further modification in shape, the nozzle there shown being adapted for use upon fluted work. In Fig. 5 I have illustrated a modified form of construction which may be employed with the various forms of edges illustrated in Figs. 3 and 4. In this form of construction, the body member consists of a circular head 23 and a cylindrical body portion proper 24 into one end of which the head is secured. The other end of the body member proper 24 is compressed to bring its edges together as shown at 25 and the edge thus formed is beveled in the manner previously described to provide the discharge slot 26 corresponding to the slot 22

of the nozzle shown in Fig. 1 of the drawing. It will of course be understood that in constructing this type of nozzle, the same care is employed in keeping the area of the slot 26 less than the area of the inlet pipe to prevent all bubbling of the paint.

Having thus described the invention, what is claimed as new is:

A paint distributing nozzle including a hollow body formed with an inlet opening, 40 said body including a head, spaced triangular side members and top and bottom members, the head being inserted between the edges of the side members and top and bottom members and the converging edges of 45 the side members being formed with tongues seating in recesses formed in the adjacent edges of the top and bottom members between which the side members seat, the members being brazed or otherwise secured 5 together and the top and bottom members, at their lower edges being beveled to form a slot between them.

In testimony whereof I affix my signature in presence of two witnesses.

JAMES S. MOE. [L.S.]
